UNITED STATES PATENT OFFICE.

HERMANN RASSBACH, OF MILWAUKEE, WISCONSIN. ASSIGNEE TO THE VILTER MANUFACTURING COMPANY, OF MILWAUKEE, WISCONSIN, A CORPORATION OF WISCONSIN.

REFRIGERATING APPARATUS.

No. 894,285.

Specification of Letters Patent.

Patented July 28, 1908.

Application filed September 14, 1903. Serial No. 173,031.

To all whom it may concern:

Be it known that I, HERMANN RASSBACH, a citizen of the United States, residing at Milwaukee, in the county of Milwaukee and State of Wisconsin, have invented certain new and useful Improvements in Refrigerating Apparatus, of which the following is a specification, reference being had to the accompanying drawing, forming a part thereof.

10 This invention relates to that class of refrigerating apparatus in which a volatile liquid is employed as the refrigerant to absorb or abstract the heat of surrounding or adjacent bodies or substances, and the gas or 15 vapor resulting from the evaporation of the liquid is liquefied, so that the same refrigerant is used over and over again in a continuous cycle.

The main objects of the invention are to 20 automatically regulate the supply of a cooling agent to a plurality of coils or chambers or to the several parts of a refrigerating system according to the varying conditions and demands in such a system, and thus overcome the difficulties heretofore experienced 25 in supplying to each of the several parts of the system the requisite quantity of cooling agent for the effective and economical operation thereof; to avoid the return of liquefied 30 gas to the compressor or other condensing apparatus; to return to the refrigerating plates or coils or to the expansion chambers all of the cooling agent which is discharged 35 therefrom in a liquid state, thereby utilizing its full efficiency; to avoid the care, trouble 40 and uncertainty incident to the manual regulation of the supply of the cooling agent to the several parts of a refrigerating system; to utilize the liquefied refrigerant condensed 45 by the operation of throwing off and liberating the finished ice from the freezing plates for immediate and effective work in active freezing coils; and generally to simplify and improve the construction and operation of apparatus of this class.

The invention consists in certain novel features of construction and in the peculiar arrangement and combinations of parts hereinafter particularly described and summarized in the claims.

In the accompanying drawing like characters designate the same parts in both figures.

Figure 1 is a diagram and sectional view of apparatus embodying the invention and 55 designed for use in the manufacture of ice;

and Fig. 2 is a perspective view of a part of the apparatus shown in Fig. 1.

Referring to Fig. 1, showing refrigerating apparatus embodying my invention, *h* designates a closed tank or reservoir, which may 60 be called an accumulator.

i designates one of a number of cooling coils or pipes, which for the purpose of more readily liberating the ice formed thereon, are covered on both sides by thin metal sheets *j*, 65 held in close contact therewith by metal straps or bars *j'* which support the several sections or parts of each coil and are bolted thereto over the edges of said sheets, as shown in Figs. 1 and 2. These sheets on the 70 opposite side of each coil are also connected and clamped to the coil by bolts at intervals between said supporting straps or bars. As they do not or need not form water tight 75 chambers for the coils and are not required to support the coils, they may be and are preferably made comparatively thin and light. Any desired number of these coils covered as above stated are arranged at suitable intervals and parallel with each other in 80 a steel or metal tank *k*, for holding the water to be frozen. The ends of the coils are connected with horizontal headers or manifolds *l* and *m*, their connections therewith being provided with stop cocks *n* and *o*, for the sole 85 purpose, as hereinafter explained, of shutting off any of said coils from said headers. The header *l* is located below and connected with the lower part of the accumulator *h* in such 90 relation thereto and to the coils that when the cocks *n* and *o* are opened, liquid will flow from the accumulator by gravity alone into and simultaneously fill or partially fill all the coils to the same level. The header *m* is located above the header *l* and is connected 95 with the accumulator at any convenient and suitable point above the bottom thereof.

The top or upper part of the accumulator *h* is connected by a pipe *p* with the suction side of a compressor *q* or other liquefying apparatus. A coil contained in a tank *r* for cooling the water with which the freezing tank *k* is supplied, is preferably connected with the pipe *p*. The discharge side of the compressor is connected by a pipe *s* with the accumulator *h*, and a cooling coil or condenser *t* and a coil *u* contained in the upper part of the accumulator or return conduit for the gas are connected in this pipe, which is provided at a convenient point between the coil *u* and the 110

accumulator, with a single regulating valve *v* controlling the pressure in the accumulator and all the evaporating and cooling coils connected therewith.

5 The freezing tank *k*, which is made of metal, is provided with an insulating jacket or casing *w*, constructed of wood, or other suitable material, and inclosing an air space along the sides and bottom of the tank. 10 This space is divided midway between and parallel with the coils by the timbers which support the tank or otherwise, into ducts or passages *x*, and these ducts communicate through ports or openings controlled by 15 valves *y*, with an air duct *z* extending along one side of the tank and connected with a source of hot or warm air.

Each of the coils *i* is connected at its upper outlet end with a header 2, which is in turn 20 connected by a pipe 3 with the discharge pipe *s* between the compressor *q* and the condenser *t*. The connection of each coil with the header 2 is provided with a valve 4.

The several spaces between the sheet metal 25 covered coils in the tank are connected with each other at the bottom by a header 5 and branch pipes 6, provided with valves 7, by means of which connections a uniform water level is maintained in the several parts of the 30 tank.

To determine and maintain a certain depth 35 of water in the tank *k* it is provided with an overflow pipe 8. The tank is supplied with water from a header 9, provided at convenient intervals with valves and hose connections 10.

Branch pipes 11 provided with valves 12, lead into the lower parts of the sections of the freezing tank from one or more compressed 40 air supply mains 13.

My improved apparatus, constructed and arranged for making ice as hereinbefore described, operates as follows: It is well known to those familiar with the art to which my 45 invention pertains, that liquid anhydrous ammonia boils, or is converted into a gaseous state at a temperature of about $\frac{1}{2}$ ° Fahrenheit below zero, and under a pressure of about fifteen pounds per square inch above that of the atmosphere. It is also well understood 50 that for converting a liquid into a gas or vapor, heat is required. If therefore, the accumulator *h* is partially filled, as shown in Fig. 1, with liquid anhydrous ammonia, at 55 the temperature and under the pressure above mentioned, this liquid will flow by gravity through the header *l* into the coils *i*, filling them all to the level of the liquid contained in the accumulator. The liquid ammonia coming in contact with the metal pipe 60 coils which have a temperature corresponding with that of the water in the freezing tank, this temperature being much higher than the boiling point of the ammonia, will 65 boil or be converted into vapor or gas, ab-

sorbing the heat for its evaporation from the coils and surrounding water. The ammonia steam or gas thus produced entraining with it more or less of the liquid ammonia, will escape from the coils through the manifold *m*, into the accumulator, where the liquid will be precipitated, while the gas separating from the liquid passes by the pipe *p*, through the forecooler *r*, to the compressor *q*, to be recompressed and returned through the condenser *t* and cooling coil *u* into the accumulator. 70 The liquid refrigerant thus returned from the coils and precipitated in the accumulator under the same pressure and hence at the same temperature as the gas escaping 75 therefrom, being available for effective work, flows again into the active freezing coils. 80

The heat of the water in tank *k* transferred to the liquid ammonia in the coils *i*, converts the same into steam or gas. It follows that 85 the temperature of the water will thus be reduced until it reaches the freezing point and congeals on the plates *j*, the ice becoming gradually thicker while the process of evaporation and circulation of the refrigerant in 90 the coils is continued. This process of evaporation is made continuous by the supply through the pipe *s* to the accumulator from the compressor of an amount of liquid ammonia equal to that escaping from the 95 accumulator in the form of gas to the compressor. The liquid ammonia returning from the compressor through the condenser to the accumulator, is of a much higher temperature and under much greater pressure 100 than are maintained in the evaporating and cooling coils of the apparatus. If the liquid ammonia were liberated from the high pressure under which it is delivered from the condenser, its sensible heat at the high temperature 105 corresponding to that pressure would be consumed at once in converting a part of such liquid into gas, and that part would be lost for effective refrigeration in the freezing coils. To prevent this loss it is necessary to deprive 110 the liquid refrigerant of its excess of sensible heat and thus destroy its *vis viva* before it is admitted into the accumulator and before it is relieved from its high pressure.

The warm liquid ammonia coming from 115 the compressor, before it enters the accumulator through the regulating valve *v* to repeat its circuit through the freezing coils, is passed through the cooling coil *u*, in which its temperature is reduced by the cold outflowing 120 gas to the temperature of the refrigerant contained in the accumulator. Being now relieved from its high pressure as it passes through the regulating valve *v* into the accumulator, no part of the liquid refrigerant 125 will evaporate since there is no heat present to cause evaporation, the accumulator being protected against the warmth of the surrounding air by a covering of non-conducting material. By regulating the supply of liq- 130

uid ammonia to the accumulator through this single valve, the proper conditions of pressure can be readily maintained in the accumulator and cooling coils, while the liquid refrigerant will be supplied and distributed automatically by gravity and by gravity alone, from the accumulator through the header *l* to the several freezing coils according to the conditions and requirements in the different parts of the system. As freezing progresses and the ice becomes thicker on the metal sheets *j* covering the coils, thereby retarding the transmission of heat from the water to the coils, the evaporation of the refrigerant within the coils becomes less active; but since the temperature of the refrigerant depends upon the pressure under which it is held, the same or even a greater congealing effect will be exerted upon the surrounding medium when the refrigerant is in a dense condition than when it is in a state of ebullition within the coils under the same pressure.

While the process of freezing is going on there is always more or less evaporation of the refrigerant in the coils and the column of dense liquid in the accumulator and its connections with the lower ends of the coils being heavier than the column of rarefied liquid rising to the same level within the coils, a constant circulation of the refrigerant through the coils is maintained, and since the liquid refrigerant is held under an invariable pressure and at an invariable temperature in the coils and accumulator, it exerts a more energetic cooling effect than a corresponding volume of vapor or gas with its comparatively small amount of specific heat.

In the practical operation of this system, about the same quantity of ice is finished and taken out of the freezing tank every day, so that while the finished product is being removed from certain parts, the process of freezing is at different stages of progress in other parts of the tank, resulting in a more or less active evaporation and circulation of the refrigerant in such parts. Nevertheless, the aggregate evaporation in the entire system remains practically constant, and therefore, the supply of liquid refrigerant to all the active freezing coils should be uniformly maintained.

It follows that the means and method of forecooling the liquid refrigerant while it is held under high pressure to the temperature of the refrigerant contained in the accumulator before it is admitted into the accumulator, the regulation or control of the supply of such refrigerant to the accumulator by a single valve and the automatic distribution and supply of the liquid refrigerant under low pressure to the several active freezing coils, according to varying conditions and demands, by gravity and by gravity alone, are essential distinctive features of the present invention.

When the ice has attained the desired thickness, say 12 to 14 inches, in certain parts of the freezing tank, it is liberated by admitting gas under pressure through the valves *4* into the corresponding coils *i*, after the cocks *n* and *o* have been closed to shut such coils off from the accumulator. The coils and thin metal sheets *j* covering them, are thus warmed by the gas, which is in turn cooled and liquefied. Instead of returning this liquefied gas to the suction side of the compressor, and thereby obstructing its action in connection with other parts of the system, it is discharged by slightly opening the valves *n* into the manifold *l*, and thus utilized under the conditions of pressure and temperature therein maintained, to supply the cooling coils which remain in operation.

To detach the ice cakes from the bottom and sides of the tank *k* to which they are also frozen, hot air is admitted to the adjoining passages *x* from the supply duct *z* by opening the proper valves *y*. The parts of the metal tank to which the ice cakes adhere are thus warmed sufficiently to release said cakes and permit their removal. As soon as, or even before, the ice cakes are removed, the process of freezing is resumed in those sections or parts of the tank from which the cakes are taken, by simply opening the cocks *n* and *o*, after closing the valves *4* of the corresponding coils. While the cakes are being removed, an equivalent volume of water is supplied to the tank from the forecooler *r* or a cold water reservoir through the header *9* and a hose attached to one or more of the valves *10*.

During the process of freezing, the water in the several parts of the tank is continuously agitated by forcing compressed air into it near the bottom of the tank through the pipes *11*. This prevents impurities which are eliminated by the freezing process from adhering to the ice cakes and becoming embedded therein, and as a result, a crystal clear product is obtained from water which has not been subjected to distillation or filtration. To render this agitation uniform throughout the freezing tank, the water in the several sections or parts of the tank, which are separated from each other by the formation of the ice, is kept at the same level by means of the connecting pipe *5* and its branches *6*, which communicate with said sections or spaces midway between the coils where no ice is formed. Without these connections the water would assume different levels in different parts of the tank, on account of the expansion which takes place with the formation of the ice and its varying thickness at different stages of its formation. Any material variation in the water level in the several parts of the tank would prevent uniform agitation of the water through which the air discharged into it takes the course of least resistance, and would result in lack of

uniformity in the purity of the ice, since greater agitation would take place in those parts in which the water level was lowest, and the ice formed in such parts would be 5 freer from impurities.

By measuring or weighing the amount of overflow of water from the outlet pipe or connection 8 for a given time, the total amount of ice produced in that time can be readily 10 ascertained, since the weight of a certain volume of water at the freezing point has a certain ratio to an equal volume of ice.

It is obvious that the principle embodied 15 in the apparatus herein shown and described may be utilized for other purposes than making ice, as for example, by omitting the freezing tank in which the cooling coils are placed, said coils either with or without the metal sheets *j* attached thereto, or evaporation 20 chambers of any suitable form, may be used to cool the surrounding air or other mediums or substances for cold storage rooms or other purposes, the effect of variations in the temperature of the air or other mediums or 25 substances surrounding or adjacent to the cooling coils upon the operation of the apparatus being the same as variations in the temperature of water in contact with said coils in the production of ice, as herein explained.

Any suitable apparatus for recondensing or reliquefying the gas after it has been evaporated in the freezing or cooling coils or chambers and returning the same in a liquid 30 state to the accumulator may be used.

Instead of warming the metal tank *k* to detach the ice therefrom by means of hot air, any other suitable means may be provided in the space between the tank and its insulation 40 jacket or casing. In short, various changes in details of construction and arrangement of parts may be made to adapt the apparatus to the various purposes to which it is applicable without materially affecting 45 its operation and without departing from the principle and intended scope of my invention.

When in the claims a "freezing coil or chamber" is mentioned it is to be understood 50 as including one or more freezing coils or chambers.

It is to be clearly understood that a distinctively novel feature of the invention is cooling the refrigerant while held under the 55 high pressure of the system to the temperature of the refrigerant in the accumulator held under the low pressure of the system, so as to bring the refrigerant into condition to flow by gravity from the accumulator to and 60 through the freezing coil or chamber.

I claim:

1. In a refrigerating apparatus, an accumulator, a freezing coil or chamber having a gravity inlet connection from the accumulator 65 and an outlet connection therewith, a supply

connection from a liquefying apparatus for the refrigerant to the accumulator, means in the supply line for releasing the refrigerant from high to low pressure, and means whereby the refrigerant while held under the high 70 pressure of the system may be given the temperature of the refrigerant in the accumulator held under the low pressure of the system.

2. In refrigerating apparatus the combination with liquefying apparatus, of an accumulator, which has a gas outlet connection with the suction side of the liquefying apparatus and a supply connection with the discharge side of said apparatus, a cooling 80 coil or chamber having a gravity inlet connection from said accumulator and an outlet connection therewith, said supply connection being provided with a valve for releasing the refrigerant from high to low pressure and 85 arranged to be exposed to the gas on its return to the liquefying apparatus from the cooling coil or chamber to give to the refrigerant while held under the high pressure of the system the temperature of the refrigerant in the accumulator under the low pressure of the system.

3. In refrigerating apparatus the combination of an accumulator having a supply connection provided with a valve for releasing the refrigerant from high to low pressure, a gas outlet connection leading from the upper part of the accumulator, a plurality of cooling coils or chambers arranged at substantially the same level with one another, 95 a header having a gravity inlet connection with said accumulator; the lower portions of the coils being connected with said header and the upper portions having outlet connections with the accumulator, and means 100 whereby the refrigerant while under the high pressure of the system may be given the temperature of the refrigerant held at the low pressure of the system within the 105 accumulator.

4. In refrigerating apparatus the combination with liquefying apparatus, of an accumulator having a gas outlet connection leading from the upper part thereof to the suction side of the liquefying apparatus and a refrigerant supply connection with the discharge side of said apparatus leading through and exposed to the gas in the upper part of the accumulator and provided with a controlling valve after its passage through the 115 same, and one or more cooling coils or chambers each having a gravity inlet connection with said accumulator and an outlet connection therewith above its inlet connection, substantially as described.

5. In refrigerating apparatus the combination with a compressor, of an accumulator having gas return and refrigerant supply connections with said compressor, means in the supply connection for releasing the re- 120 125 130

frigerant from high to low pressure, means whereby the refrigerant while held under the high pressure of the system may be given the temperature of the refrigerant in the act 5 cumulator under the low pressure of the system, the header having a gravity supply connection with the accumulator; a plurality of freezing coils or chambers the lower parts of which are connected with said header and 10 the upper parts of which have outlet connections with the accumulator, stop cocks in the connections of said coils or chambers with

said header and with the accumulator, direct valve-controlled connections between the several coils or chambers and the compressor, 15 and a freezing tank containing said coils or chambers, substantially as described.

In witness whereof, I hereto affix my signature in presence of two witnesses.

HERMANN RASSBACH.
